UNITED STATES PATENT OFFICE.

LUCENE L. GOODENOW, OF BATTLE CREEK, MICHIGAN.

DESIGN FOR A STATUETTE.

60,952.

Specification for Design.

Patented May 16, 1922.

Application filed April 22, 1921. Serial No. 463,635. Term of patent 3½ years.

To all whom it may concern:

Be it known that I, LUCENE L. GOODENOW, a citizen of the United States of America, and a resident of the city of Battle Creek, county of Calhoun, State of Michigan, have invented a new, original, and ornamental Design for a Statuette, of which the following is a specification, reference being had to the accompanying drawing, forming part thereof.

The drawing is a perspective view of the statuette, showing my new design.

I claim:

The ornamental design for a statuette, as shown.

LUCENE L. GOODENOW.
